UNITED STATES PATENT OFFICE.

FREDERICK M. MURPHY, OF CHICAGO, ILLINOIS.

FUEL-FEED SYSTEM.

1,024,351.

Specification of Letters Patent. Patented Apr. 23, 1912.

Application filed November 18, 1911. Serial No. 661,128.

To all whom it may concern:

Be it known that I, FREDERICK M. MURPHY, a citizen of the United States, residing at Chicago, in the county of Cook and State of Illinois, have invented new and useful Improvements in Fuel-Feed Systems, of which the following is a specification.

This invention relates to a fuel feed system for automobiles, for the supply of gasoline or other hydrocarbon fuel employed to the driving motor.

The object of the invention is to provide means whereby the owner of the car, when he desires to retire the car for the night or any determined period, may cut off the feed of the hydrocarbon from the main reservoir, in such manner that the flow cannot be restored except by him or a duly authorized person, leaving only sufficient hydrocarbon in the line of feed to run the car a determined distance, whereby the owner of the car is assured that the car cannot be surreptitiously operated while it is in supposed retirement.

25 The invention consists of the features of construction, combination and arrangement of parts, hereinafter fully described and claimed, reference being had to the accompanying drawings, in which:—

30 Figure 1 is a sectional view showing the application of the invention to an automobile of the touring car type. Fig. 2 is a top plan view of certain parts shown in Fig. 1. Fig. 3 is a longitudinal section through the auxiliary supply tank on an enlarged scale. Figs. 4 and 5 are sectional views through the cut-off valve, showing the same in open and closed position. Fig. 6 is a 35 sectional elevation showing the application 40 of the invention to an automobile of the roadster type.

Referring to the drawings, 1 designates the main fuel supply tank, 2 the motor, and 3 the carbureter of an automobile driving apparatus, which parts may be mounted upon the vehicle in any desired or required manner.

45 In carrying my invention into practice, I provide an auxiliary reservoir or supply tank 4 arranged in the line of feed between the main supply tank 1 and carbureter 3, which tank 4 is of relatively smaller size than the tank 1 to contain only a sufficient charge for supply of the fuel to run the vehicle a determined distance.

50 The tank 4 is connected at its inlet end

with the main supply pipe by a suitable inlet pipe or connection 5, and is connected at its outlet or discharge end with the carbureter by a feed pipe 6, said inlet and feed pipes forming part of the flow connection between the main reservoir and the motor.

55 Arranged in the inlet pipe 5 is a cut-off or controlling valve 7, which valve is preferably of the tapered-plug type and provided with a passage 8 for opening communication between the main and auxiliary tanks when said valve is in open position. Communicating with the passage 8 is a cross passage 9 adapted, when the valve is 60 closed, to cut off the flow of hydrocarbon from the main tank to the supplementary tank, and to communicate with an air inlet 10 in the valve casing for the admission of air to said auxiliary tank to compensate 65 for the feed of the hydrocarbon therefrom.

70 The tank 4 may be secured in any suitable manner to the tank 1 or body of the vehicle, or in any desired position between the main tank and carbureter, and, when a carbureter 75 is not employed, the line of feed may be directly from the auxiliary tank to the motor.

75 Fixed to the casing of the valve 7 or to some other suitable support is a bracket arm 80 provided with an opening 12, and connected with the valve plug is an arm or lever 13 having an opening 14 to register with the opening 12 when the valve is closed. The lever 13 is arranged in such position as to be conveniently operated to open and 85 close the valve 7. The openings 12 and 14 are of proper form to receive the hasp of a suitable lock 15 which is adapted to be opened by an arbitrary type of key carried by the owner of the vehicle, or other duly 90 authorized person.

95 In practice, the main reservoir 1 may be of a size to hold any desired quantity of hydrocarbon, while the auxiliary tank 4 is of a size to hold a comparatively small quantity, sufficient only to supply the motor to run the vehicle a limited distance. It will thus be understood that the owner of the car desiring to retire the car for the night or for any determined period may close the 100 valve 7 and lock it in closed position, thus cutting off communication between the main supply tank and the motor, and permitting only of the feed to the motor of the restricted quantity of hydrocarbon contained in the auxiliary reservoir 4. This restricted quantity of hydrocarbon may be sufficient to sup-

ply enough fuel for a trip to and from a garage, or to run the vehicle only a limited number of miles, so that upon retiring the car the owner can feel assured that the car 5 can only be run a limited distance and cannot be operated any considerable distance by an unauthorized person during its supposed retirement.

It is, of course, to be understood that the 10 invention is not limited to the particular construction, proportion or arrangement of parts herein shown, as these may be modified within the scope of the appended claims, as circumstances may require.

15 In Fig. 1 I have shown the application of the invention to an automobile of the touring car type, wherein the tanks are arranged in the compartment 16 beneath the seat and the tank 4 is secured to the underside of the 20 tank 1, the lever and bracket arm projecting outwardly through a slot 17 in the front wall of said compartment, while in Fig. 6 I have shown the application of the invention to an automobile of the roadster type, where- 25 in the tank 1 is supported upon the back of the car body, the tank 2 secured to the bottom of the car body and the bracket arm and lever disposed in the space beneath the main tank, where they may be conveniently 30 reached.

Having thus described the invention, what I claim as new is:

1. In an automobile fuel feed system, a motor, a main fuel reservoir, an auxiliary 35 fuel reservoir in the line of feed between the main fuel reservoir and the motor, a valve controlling communication between said reservoirs, said valve being adapted in its open position to permit flow of fuel from 40 one reservoir to the other and in closed po-

sition to cut off the flow of fuel between said reservoirs and admit of the access of air to the auxiliary reservoir, and means for locking said valve in closed position.

2. In a fuel feed system for automobiles, 45 a motor, a main fuel reservoir, an auxiliary fuel reservoir in the line of feed between the main reservoir and motor, a valve controlling communication between said reservoirs, said valve being operative in one po- 50 sition to establish communication between the reservoirs and in another position to close communication between the reservoirs and open communication between the auxiliary reservoir and the atmosphere, a lever 55 for operating the valve, and means for locking said lever to said stationary bracket member to hold the valve closed.

3. In an automatic fuel feed system, a motor, a main fuel reservoir, an auxiliary 60 fuel reservoir in the line of feed between the main fuel reservoir and the motor, a valve casing in the line of feed between said reservoirs, said casing having an air inlet, a valve in said casing provided with a passage 65 adapted when in open position to establish communication between the reservoirs and when in closed position to register with said air inlet and establish communication be- 70 tween the atmosphere and the auxiliary res- ervoir, an operating member for adjusting said valve, and means for locking said operating member in valve-closing position.

In testimony whereof I affix my signature in presence of two witnesses.

FREDERICK M. MURPHY.
